(57) **ABSTRACT**

A new distinct variety of grapevine named 'ARD45' abundantly forms attractive crunchy seedless berries with a red skin coloration, lax and large clusters which display a Labrusca flavor commonly ready for harvesting during July-August in San Joaquin Valley of Central California, U.S.A., and displays good eating qualities as a table grape having a firmness that renders the fruit well amenable for handling, shipping, and storage.

1 Drawing Sheet

1

Classification: The present invention relates to a new *Vitis vinifera* Grapevine.

Variety denomination: The new Grapevine has a varietal denomination 'ARD45'.

BACKGROUND OF THE INVENTION

A breeding program was initiated during the late 1990's near Bakersfield in San Joaquin Valley of Central California. In 2016, during this breeding program, a new variety of *Vitis vinifera* was created by deliberate cross breeding of two parent plants by emasculation of the pollen bearing organ of the female and introducing pollen from another male origin. The female parent of the new variety was 107C-70+4 which is a very fertile and crunchy seedless red table grape variety (non-patented in the United States). The male parent (i.e. the pollen parent) of the new variety was 26-6+3, a fertile and crunchy seedless white variety (non-patented in the United States).

TABLE 1

'ARD45' compared with parents & closely related variety:				
	'ARD45'	107C-70+4	26-6+3	(non-patented) 'Flame'
Berry shape	Broad ellipsoid	Narrow ellipsoid	Ovoid	Globose
Berry color	Red	Red	White	Greyish red
Harvest Time	Mid-season	Mid-season	Early	Very early

The parentage of the new variety can be summarized as follows:

107C-70+4 X 26-6+3

2

An artificial pollination was created, and the result was an embryo which possessed unique genetic qualities. The rudiments resulting from the above pollination were embryo rescued.

5 In 2017 the plant was transplanted to Bakersfield in San Joaquin Valley of Central California.

It was found that the new grapevine of the present invention possesses the following combination of characteristics:

- 10 (a) Forms attractive crunchy seedless berries with a red skin coloration; in lax and large clusters which display a Labrusca flavor,
- (b) Commonly bears fruit during the months of July-August in the San Joaquin Valley of Central California, U.S.A., and
- (c) Bears fruit that is firm and is well amenable for storage, handling, and shipping.
- (d) Produces 36 bunches per vine and an average of about 20 2 bunches per shoot, at a total of 43 lbs. fruit per vine.

The new variety during observation to date has displayed no visible disease, and has displayed an ability to well resist cold, drought, heat; but sensitive to direct exposure to sun and wind. The fruit of the new variety has been found to 25 display excellent handling and shipping qualities combined with desirable dessert eating qualities.

The new variety of the present invention has been found to undergo asexual propagation beginning in 2018 near Bakersfield in the San Joaquin Valley of Central California,

30 U.S.A. by bud grafting on mature 'Thompson Seedless' rootstock (non-patented in the United States). Such asexual propagation has been conducted thereafter in successive years to date and has shown that the characteristics of the new variety are strictly transmissible from one generation to

another. Accordingly, the new variety undergoes asexual propagation in a true to type manner.

SUMMARY OF THE INVENTION

The new variety 'ARD45' is a red seedless table grape with a high production, e.g., about 36 bunches per vine and an average of about 2 bunches per shoot.

Asexual reproduction by micro propagation of the new variety as performed near Bakersfield, Calif., U.S.A., shows that the forgoing and other distinguishing characteristics come true to form and are established and transmitted through succeeding propagations.

BRIEF DESCRIPTION OF THE DRAWING

The accompanying photographic illustration shows typical six-year-old specimens of the new variety, vegetatively propagated, in color as nearly true as it is reasonably possible to make in a color illustration of this character. Colors in the photograph may differ from the color values cited in the detailed botanical description below, which accurately describes the colors of the new Grapevine.

The drawing shows leaves, stems and grapes of 'ARD45'.

DETAILED BOTANICAL DESCRIPTION

The chart used in the identification of colors is The R.H.S. Colour Chart of The ROYAL HORTICULTURAL SOCIETY (3rd Edition). The description is based on the observation of plants growing on 'Thompson Seedless' rootstock outdoors near San Joaquin Valley of Central California, U.S.A.

VINE CHARACTERISTICS:

Vigor	Vigorous upright shoots
Productive capacity	Bearing at a natural, average capacity.
Trunk	Spur pruning. Strong and developed. Diameter is 3 inches at 15.5 inches above ground. Rough with a fibrous, shaggy exterior. Light brown coloring - Greyed orange 177B

Date of bud burst in Bakersfield Calif.: March 7th

YOUNG SHOOT CHARACTERISTICS:

Openness of tip	Wide open
Density of prostrate hairs on tip	Very dense
Anthocyanin coloration of prostrate hairs on tip	None
Density of erect hairs on tip	Medium

YOUNG LEAF CHARACTERISTICS:

Color of upper side of blade	Yellow green 152B
Color of lower side of blade	Yellow green 152C
Density of erect hairs between main veins on upper side of blade	Sparse
Density of erect hairs between main veins on lower side of blade	Sparse

-continued

YOUNG LEAF CHARACTERISTICS:

5	Density of prostrate hairs on main veins on upper side of blade	Absent or very sparse
	Density of prostrate hairs on main veins on lower side of blade	Absent or very sparse

SHOOT CHARACTERISTICS:

10	Attitude (before tying)	Erect
	Color of dorsal side of internodes	Yellow green 152B
	Color of ventral side of internodes	Yellow green 144C
15	Color of dorsal side of nodes	Yellow green 152A
	Color of ventral side of nodes	Yellow green 144B
	Density of erect hairs on internodes	Absent or very sparse
	Density of prostrate hairs on internodes	Sparse
	Length of tendrils	6.5 inches
20	Diameter of tendrils	0.06 inches
	Color of tendrils	Yellow green 152C
	Number of tendrils at bloom	4
	Positioning of first flowering and fruiting node	The first bunch is in the 3 rd node
	Inflorescence number per flowering shoot	2

FLOWER CHARACTERISTICS:

30	Reproductive organs	Fully developed stamens and fully developed gynoecium
	Flower length	0.26 inches
	Flower diameter	0.22 inches
	Pistil length	0.16 inches
	Pistil color	Yellow green 144A
	Pollen Amount	Rich
	Pollen color	Yellow 11B
	Stamen color	Yellow green 145C
	Stamen length	0.11 inches
35	Number of stamen	5

First bloom in Bakersfield, Calif.: April 18th

Date of full bloom in Bakersfield, Calif.: April 25th

MATURE LEAF CHARACTERISTICS:

45	Size of blade	6.5 inches x 6.5 inches
	Shape of blade	Wedge-shaped
	Base descriptors	Wedge-shaped
	Leaf margin	Serrate
	Leaf apex	Acute
	Blistering of upper side of blade	Absent or very sparse
	Depth of upper lateral sinuses	Medium
	Number of lobes	Five
	(Only varieties with lobed leaves)	Open
	Arrangement of lobes of upper lateral sinuses	
	Arrangement of lobes of petiole sinus	Wide open
	Length of teeth	0.3 inches
	Ratio length/width of teeth	Small
	Shape of teeth	Mixture of both sides straight and both sides convex
50	Density of prostrate hairs between main veins on lower side of blade	Absent or very sparse
	Density of erect hairs on main veins on lower side of blade	Absent or very sparse
	Density of erect hairs between the main veins on upper side of blade	Absent or very sparse

-continued

MATURE LEAF CHARACTERISTICS:		
Density of prostrate hairs on main veins on upper side of blade	Absent or very sparse	5
Length of petiole compared to length of middle vein	Moderately shorter	
Top side color	Green 137B	
Bottom side color	Yellow green 146B	
Texture of upper side of blade	Little rough	10
Texture of lower side of blade	Rough	
Vein color on upper blade	Yellow green 146C	
Vein color on lower blade	Yellow green 145C	
Venation pattern for upper blade	Netlike venation	
Venation pattern for lower blade	Netlike venation	
Petiole length	4.4 inches	15
Petiole diameter	0.12 inches	
Petiole color	Yellow green 145B	
Petiole texture	Smooth	
Date of beginning of berry ripening in Bakersfield Calif.: July 21 st		
BUNCH CHARACTERISTICS:		
Size (peduncle excluded)	Large	20
Density of berries on bunch	Lax	
Bunch length	9.5 inches	
Bunch diameter	5.8 inches	
Length of peduncle of primary bunch	1.2 inches	
Diameter of peduncle of primary bunch	0.11 inches	
Peduncle of primary bunch color	Yellow green 145C	25
Peduncle texture	Little Rough	
Bunches per vine	36	
Average bunch weight	1.2 lbs	
BERRY CHARACTERISTICS:		
Size	Medium	30
Length	0.9 inches	
Weight	0.2 oz	
Diameter	0.8 inches	
Shape	Broad ellipsoid	
Color of skin (without bloom)	Red 46A	
Flesh color	Yellow green 145D	
Brix	25.1	
Titratable acidity percentage	0.4%	
Juice	4 pH	
Ease of detachment from pedicel	Moderately easy	35
Thickness of skin	Medium	
Anthocyanin coloration of flesh	None	
Firmness of flesh	Moderately firm	
Particular flavor	Foxy	
Formation of seeds	Rudimentary	
Berries per bunch	115	
PEDICEL CHARACTERISTICS:		
Length	0.31 inches	40
Diameter	0.08 inches	
PEDICEL CHARACTERISTICS:		
Color	Yellow green 145B	45
Pedicel texture	Rough	
WOODY SHOOT CHARACTERISTICS:		
Woody shoot texture	Rough	50
Woody shoot color	Greyed orange 166B	
Woody shoot length	138 inches	
Diameter	0.36 inches	
Internode length	4.4 inches	
Market use of observed plants: Fresh market.		
Age and growing conditions: Six years growing under Y system in South Joaquin Valley (hot, dry summers).		
Shipping characteristics: Fruit was in cold storage. Stored in poly bags inside Styrofoam boxes with sulfur pads. After 60 Days: rachises were 10% green; 0% berry shattering; no berry wrinkling or cracks were apparent.		
DNA profile: To further the characterize the new variety DNA was extracted from plant samples and a DNA profile was obtained in California USA using base pairs for 10 standard microsatellite DNA markers. The data is presented hereafter.		
TABLE 2		
DNA profile for 'ARD45'		
Microsatellite DNA Marker		
Allele Sizes in Base Pairs		
M 1	228	234
M 2	249	249
M 3	185	194
M 4	212	220
M 5	253	265
M 6	123	135
M 7	205	205
M 8	255	255
M 9	214	214
M 10	221	233
The 'ARD45' variety has not been observed under all possible environmental conditions to date. Accordingly, it is possible that the phenotypic expression may vary somewhat with changes in light intensity and duration, cultural practices, and other environmental conditions.		
Additional information relating to plant and fruit disease and pest resistance or susceptibility has not been observed to date. Specification of the plant hardiness zone and the heat/cold resistance has not been observed to date.		
What is claimed is:		
1. A new and distinct grapevine plant, botanically known as <i>Vitis vinifera</i> , identified as 'ARD45', substantially as shown and described herein.
